TOWEL CABINET

Application filed November 23, 1929. Serial No. 409,317.

This invention relates generally to dispensing apparatus and has particular reference to towel dispensing holders.

The invention concerns itself more particularly with towel cabinets of the so called automatic type wherein means is provided for controlling the amount of toweling allotted each user.

While cabinets of the foregoing character have achieved considerable recognition in the trade as a conservative means of dispensing toweling, nevertheless a great many of these cabinets have proved objectionable since it is possible to obtain only a limited amount of toweling out of the cabinets at predetermined intervals. As a consequence, if the user does not find the allotted quantity of toweling sufficient for his needs, it is necessary for him to either wait until the time limit has expired before he is able to get another portion of toweling or to use the soiled toweling, which of course is exceedingly unsanitary.

It is therefore one of the essential objects of this invention to eliminate the foregoing objections by providing retarding means for the towel feeding mechanism which does not positively stop passage of the toweling out of the cabinet as is the case in many types of cabinets now commercially produced, but on the other hand merely retards the passage of toweling after a portion of the same has been extracted. In other words, with the present invention, if the user persists in pulling the toweling after the portion aforesaid has been withdrawn, he will be able to secure additional toweling, but only at a comparatively slow constant speed irrespective of the force exerted upon the toweling. This arrangement, in addition to affording sufficient toweling without material loss of time, also prevents extravagant use of the toweling.

Another object of this invention resides in the provision of automatic mechanism for taking up substantially the exact amount of toweling allotted to the user after the same has served its purpose. With this construction, the loop of toweling below the cabinet is maintained at a constant length.

Still another object of this invention resides in the provision of automatic take-up

mechanism of the above type operable to take up the soiled toweling at a slow rate of speed so that a convenient length of toweling is maintained below the cabinet or holder at all times.

A further object of this invention is to provide automatically operable means for winding the final length of toweling around the take-up roll and to associate with this means mechanism requiring the various parts of the device to be restored to their initial operative positions before a new roll of toweling can be operatively assembled within the cabinet.

A still further object of this invention resides in the means for mounting the towel roll within the cabinet which not only facilitates replacing the roll but also simplifies the construction and thereby reduces the cost of manufacture to the minimum.

This invention also contemplates a sliding door for the cabinet which when in its lowermost position serves as a gauge for the attendant to determine the length of the loop required below the cabinet for convenient operation, and which is so constructed as to resist accidental opening thereof by any force applied to the toweling.

With the foregoing, as well as other objects in view, the invention resides in the peculiar construction and arrangements of parts which will be made more fully apparent as this description proceeds, especially when considered in connection with the accompanying drawings wherein:

Figure 1 is a side elevational diagrammatic view of the towel cabinet with portions broken away for the sake of clearness;

Figure 2 is a longitudinal sectional view through the cabinet;

Figure 3 is a sectional view taken on the plane indicated by the line 3—3 of Figure 2;

Figure 4 is a sectional view taken on the line 4—4 of Figure 2, showing the position the parts assume when the final length of toweling is being withdrawn from the towel roll;

Figure 4A is a plan view of Figure 7;

Figure 5 is a detailed sectional view show-

ing the sliding connection between the door and cabinet;

Figure 6 is a detailed sectional view taken on the line 6—6 of Figure 2;

5 Figure 7 is a detailed diagrammatic view of the towel roll feeding mechanism showing various positions of the lugs;

10 Figure 7A is a view similar to Figure 7 but more complete and showing the front face of the lug on the dog in engagement with the stud of a power unit; and

15 Figure 7B is a view similar to Figure 7A showing the position of the dog when the lug thereof is disengaged from the recess.

15 Generally described, there is illustrated in the drawings a towel cabinet 10 comprising a casing 11 having an open front side adapted to be closed by a suitable sliding door 12. Arranged within the casing 11 adjacent the upper end thereof is a towel roll 13 carrying a supply of clean toweling designated at 14. As shown particularly in Figure 1 the toweling is wound around the roll 13 and a portion of the same is extended 20 along the inner surface of the door 12 through a suitable opening 15 formed in the bottom of the casing. The toweling is then looped back into the casing through a similar slot 16 in the bottom of the cabinet adjacent the rear wall thereof and is suitably attached to a second roll 17 for taking up the soiled toweling. The take up roll is mounted in the lower portion of the casing in spaced relation to the clean supply of 25 toweling so as not to come in contact therewith. In order to insure proper spacing of the clean toweling from the soiled, a suitable guide roll 18 is provided adjacent the front side of the casing and intermediate the two 30 rolls. Extending transversely of the casing beneath the rolls 13 and 17 respectively are the actuating rolls 19 and 20. These rolls are provided with roughened surfaces 21 adapted for frictional contact with the toweling on each of the rolls 13 and 17.

50 In order to maintain frictional engagement between the rolls of toweling and the actuating rolls 19 and 20, the rolls 13 and 17 are mounted to swing in an arc of a circle so that engagement between the towel rolls and actuating rolls will be insured at all times irrespective of the diameter of the towel rolls. This is accomplished in the 55 present instance by attaching the rolls 13 and 17 to the free ends of the arms 21 having the opposite ends pivotally connected to opposite side walls of their casing as clearly shown in Figure 1.

60 The door 12 slidably engages the side walls of the casing and preferably slides in the direction of movement of the toweling to open position. The arrangement is such that when the toweling is pulled outwardly by the user against the inner bottom edge of the 65 door, there will be no danger of the same fly-

ing open and injuring the user as would be the case if the door was hinged to swing outwardly. Moreover, by providing a door of the above character, replacing of toweling within the cabinet is greatly facilitated since the length of the door is so selected as to be substantially equal to the length of the loop of toweling that should be left exposed below the casing. As a consequence when the door is in its open position, as indicated in Figure 5, it serves as a gauge for the attendant and insures a convenient length of toweling below the cabinet.

70 Referring now more in detail to the towel actuating mechanism and with special reference to Figure 2 of the drawings, it will be noted that one end of the roll 19 is journaled in a bracket bearing 22 secured to one side wall of the casing, while the opposite end of the roll has secured thereto a shaft 23 extending through an opening 24 formed in the opposite side wall 24' of the casing and journaled in a bracket bearing 25 suitably secured to the casing wall 24'. Mounted upon the shaft 23 adjacent the outer end thereof is a power actuated unit 26 comprising a spring 27 having one end secured to a sleeve 28 which in turn is secured to the shaft 23. The opposite end of the spring is secured to a pin 29 extending longitudinally of and spaced from the shaft 23. Freely rotatably mounted upon the shaft 23 upon opposite sides of the sleeve 28 is a gear 30 and a sprocket 31, connected together for rotation as a unit about said shaft by means of the pin 29. See Figure 2. The latter is preferably secured to the sprocket 31 adjacent the periphery thereof so that the maximum turning force will be imparted to the gear 30 by the spring. Thus it will be apparent that the gear 30 and sprocket 31 are rotated about the shaft 23 by means of the spring 27.

75 In order to control the speed of rotation of the gear 30 and sprocket 31 so that the same will be actuated at a comparatively slow rate of speed, I provide a governor 32, preferably of the centrifugal type, comprising a cup-shaped casing 33 having the base portion thereof secured to outer side of the wall 24' adjacent the lower end thereof by means of a fastening element 34. Rotatably mounted upon a bushing surrounding said fastening element, is a gear 35 carrying a plate 36 having a diameter substantially equal to the inside diameter of the casing 33 and which carries a pair of brake shoes 37 and 38. These shoes are preferably of the shape illustrated in Figure 3, and each has one end pivotally connected to the plate 36 adjacent the periphery thereof and at substantially diametrical- 80 ly opposite sides of the same. The opposite ends of the shoes are free to swing outwardly into frictional contact with the annular flange of the cup-shaped casing and thereby retard rotation of the gear 35. The free ends 85

of the shoes are normally restrained from outward movement by means of springs 39 carried by a disk 40 mounted for rotary adjustment about the fastening element 34 to 5 adjust the tension of the springs and thereby control the operation of the governor. The disk is locked in adjusted position upon the plate 36 by means of screws 41 extending through slots 42 in the disk and threaded into the plate 36. The gear 35 of the governor is connected to the gear 30 by suitable gearing designated generally by the character 10 43. The arrangement is such that the gear 30 and sprocket 31 will be rotated at a comparatively slow rate of speed irrespective of any force tending to accentuate rotation thereof.

The foregoing mechanism is designed to retard the speed of rotation of the roll 19 20 after a portion of toweling has been withdrawn from the roll 13. This is accomplished in the following manner: Secured to the end of the roll 19 so as to rotate as a unit therewith is a plate 44 having a diameter substantially greater than the roll 19 and 25 having a dog 45 pivotally secured thereto adjacent the periphery thereof, as shown in Figures 4, 7, 7A, and 7B. The dog 45 projects beyond the periphery of the plate 44 and is provided with an inwardly extending lug or check 46 adapted to be engaged by a 30 stud 47 carried by the gear 30. With the construction as thus far described and assuming that the stud 47 is in rear of the lug 46 and 35 engaged therewith as shown in Figure 7 to prevent rotation of the power unit 26, and that the user exerts a downward pull upon the loop of toweling below the cabinet, it will be noted that the roll 19 will be rotated 40 in a direction to move the lug 46 away from the stud 47 and subsequently cause the front face 47' of the lug to engage the opposite side of the stud 47, as shown in Figure 7A. As 45 soon as the lug 46 is moved away from the stud 47 the latter is actuated by the power unit, through the governor 32 and reduction gearing 43, in a corresponding direction of rotation until the stud 47 again contacts with the rear face of the lug 46, as shown in Figure 50 7, at which time rotation of the power unit is again arrested. This is assuming that the user releases the toweling as soon as the face 47' of the lug 46 engages the stud 47, as shown in Figure 7A. In the event that 55 the user does not release the toweling when the face 47' of the lug 46 engages the stud 47, but on the other hand continues to pull on the towel, it will be noted that the lug 46 will be compelled to follow the stud 47 at 60 the speed of the latter, which is comparatively slow due to the governor 32 and reduction gearing connecting the governor with the gear 30. As a consequence, additional toweling is furnished in accordance with the speed 65 of rotation of the gear 30, irrespective of the

force exerted upon the toweling by the user.

Thus it will be apparent that the above described mechanism does not prohibit the withdrawal of toweling from the cabinet at any time but on the other hand merely retards the passage of toweling after a portion of the latter has been withdrawn. The arrangement is such as to afford sufficient toweling for the user without material loss of time as well as to prohibit extravagant use of the toweling.

As shown particularly in Figure 3 of the drawings, the sprocket 31 is connected by means of a chain 48, to a sprocket 49 mounted upon the roll 20. With this construction, whenever the power actuated mechanism 26 is in operation, the roll 20 will also be operated to take up the soiled toweling and owing to the stop arrangement hereinbefore set forth, the extent of rotation of the roll 20 will correspond to the rotation of the roll 19 so that the amount of toweling taken up will equal the amount of toweling withdrawn from the roll 13. In this connection, it will also be noted that when the spring 27 is unwound one revolution, for example, to actuate the take up mechanism and to bring the lugs 46 and stud 47 into their initial operative positions as shown in Figure 7, it is subsequently re-wound to exactly the same tension when the user withdraws another portion of toweling. This is due to the fact that the sleeve 28 forming an anchor for the inner end of the spring rotates with the roll 19.

When the supply of toweling on the roll 13 is substantially exhausted, or in other words, when the roll 13 assumes the dotted line position indicated by the reference character 50 in Figure 1 of the drawings, it is desirable to provide some means for winding the final length of toweling within the cabinet around the take up roll 17. This is accomplished in the present instance by the following mechanism: Freely rotatably mounted upon the shaft 23 between the gear 30 and plate 44, is a gear 51 having a hub portion 52 terminating in a lug 53 adapted for engagement with a corresponding lug 54 projecting from the gear 30, as best shown in Figure 2. The gear 51 is connected by suitable reduction gearing illustrated generally by the character 55 to a gear 56 mounted upon the plate 44 adjacent the periphery thereof, as shown in Figures 4, 7A and 7B. The gear 56 has secured thereto a disk 57 provided with a recess 58 adapted to receive the lug 46 upon the dog 45 and thereby hold the lug in a position to be engaged by the stud 47 in the manner hereinbefore set forth, and as shown in Figure 7. The arrangement is such that when the lug 46 is in engagement with the recess 58, or in other words, is in the path of movement of the stud 47, the gear 56 and reduction gearing 55 will be prevented from rotation relative to

the plate. Thus it will be seen that in the normal operation of the mechanism, the gear 56 and reduction gearing 55 will be locked against relative rotation by the lug 46, and will therefore move as a unit with the plate 44.

In order to lift the dog 45 out of the recess 58 and thereby permit free actuation of the power unit 26 to operate the takeup roll 20 to wind up the final or tail end of the towel, a lever 59 is secured to one of the supporting arms 21 for the towel roll 13 and has the end portion thereof spaced slightly above the arm 21 so that when the lever 59 is in the position shown by the dotted lines of Figure 1, the end of the arm will be in a position to engage the free end 45' of the dog 45 and swing the latter outwardly upon movement of the roll 19, the dog being normally held from outward movement by means of a suitable leaf spring 61 having one end secured to the plate and the other end bearing against the dog.

Referring now to the operation of the mechanism just described, it will be noted that when substantially all of the toweling has been withdrawn from the roll 13, the lug 46 will be automatically moved out of engagement with the recess 58 by the lever 59, and also out of the path of travel of the stud 47, as shown in Figure 4. When the lug 46 is thus positioned, the power unit 26 will be capable of free rotation about the shaft 23 relative to the roll 19, and owing to the connection between the sprocket 31 and roll 20 the latter will be actuated to take up the final length of toweling within the cabinet.

During rotation of the power unit 26, the lug 54 on the gear 30 will engage the face 63 of the lug 53 and rotate the gear 51 in a counterclockwise direction as shown in Figure 4. Rotation of the gear 51 in this direction will effect a rotation of the gear 56 through the reduction gearing 55 in a clockwise direction to move the recess 58 out of registration with the lug 46. As a consequence, before the lug 46 can re-engage within the recess it is necessary to rotate the gear 56 in a counterclockwise direction the same distance it has previously moved in a clockwise direction during the taking up of the soiled toweling. This is accomplished by disengaging the lever 59 from the dog 45, as shown in the dotted lines in the upper portion of Figure 4, whereby the spring 61 will move the dog to the position shown in Figure 7B, wherein it is to be noted that the lug 46 of the dog will be engaged with the periphery of the disk 57. The attendant then manually rotates the roll 19 in the direction indicated by the arrow at the right hand side of Figure 4, whereby a similar movement will be imparted to the circular plate 44 and shaft extension 23 because of these parts being fixed to the roll. Upon initial movement of the roll 19, following release of the dog 45, the lug 53 of the

gear 51 will move out of engagement with the lug 54 of the gear 30 of the power unit 26, because of the gear 51 rotating synchronously with the plate 44, it being understood that there is no relative rotation between the gears 50 70 and 56 of the reduction gears 55, upon such initial rotation of the roll 19 and plate 44. Before the plate 44 has been rotated one revolution, the lug 53 of the gear 51 will engage the opposite side of the lug 54 of the gear 30, whereby rotation of the gear 51 with the plate 44 is interrupted, thereby causing the reduction gearing 55 to function and relatively rotate the disk 57 of the gear 56 about its center in a counterclockwise direction or, 80 in other words, in a direction opposite to the direction of movement thereof during the taking up of the soiled toweling.

Rotation of the roll 19 is continued until the lug 46 returns to its normal position in the recess 58, as shown in Figures 7 and 7A, whereby relative rotation of the gear 56 is interrupted, and the lug 46 is again positioned in the path of the stud 47 of the power unit gear 30. When this occurs, the spring 27 will be rewound to its exact initial operating tension, and the entire mechanism will be restored to its normal operating condition. A fresh roll of toweling may then be inserted into the cabinet, as hereinbefore described, after which the cabinet is ready for use. During normal operation of the cabinet, the lug 46 of the dog 45 will be retained in the recess 58, it being moved out of the recess only when the lever 59 engages the end portion 45' of the dog, as shown in Figure 4.

Thus from the foregoing, it will be apparent that I have provided mechanism which in addition to taking up the final length of toweling within the cabinet, also requires the spring 27 to be re-wound to its exact initial tension before a new roll of toweling can be operatively installed within the cabinet.

In order to restrict rotation of the roll 19 in a clockwise direction, I provide a suitable stop 65 comprising a bracket 66 secured to the inner side wall of the casing adjacent the periphery of the plate 44 and having a tapered groove 67 therein adapted to receive a ball 68 normally arranged in the enlarged portion of the recess 67 and engageable with the periphery of the plate 44. The arrangement is such that when the roll is moved in a counterclockwise direction, the ball 68 will assume a position in the enlarged portion of the recess 67 so as not to retard rotation of the roll 19. In the event, however, an attempt is made to revolve the roll 19 in a clockwise direction, the ball 68 will engage the reduced portion of the recess 67 and lock the roll against such rotation.

Thus from the foregoing, it will be apparent that I have provided a towel cabinet which, in addition to possessing the advan-

tages hereinbefore discussed, is comparatively simple in construction and may be manufactured, assembled and installed with facility.

5. While one embodiment of the invention has been described herein somewhat in detail, the structure shown is for illustrative purposes only and the non-essential details herein shown and described should not be 10 considered as limiting in any respect the essentials and principles of the invention. Furthermore, it may be possible to modify and rearrange the most essential principles of the invention without departing from the scope 15 thereof and to this end reservation is made to make such changes as may come within the purview of the accompanying claims.

What I claim as my invention is:

1. A towel holder having in combination, 20 means for dispensing toweling, and means automatically set into operation by the dispensing operation, said means being operable after a portion of toweling has been withdrawn to retard the movement thereof.

25. 2. A towel holder having in combination, means for dispensing toweling, and means operable automatically after a portion of the toweling has been withdrawn to retard but allow movement thereof irrespective of the 30 force exerted upon the same.

35. 3. A towel holder having in combination, a towel roll containing a supply of toweling and adapted to be actuated by the user to dispense the toweling, means whereby a portion of the toweling may be withdrawn in accordance with the force exerted upon the latter by the user, and means operable after the portion aforesaid of the toweling has been withdrawn to change the speed of said roll 40 irrespective of the force exerted by the user.

45. 4. A towel holder having in combination, means for dispensing toweling adapted for actuation by a force exerted upon the toweling by the user, a portion of said towel being freely dispensed, and means operable after the portion aforesaid of the toweling has been withdrawn to compel operation of said dispensing means at a comparatively slow rate of speed irrespective of the force exerted upon the toweling by the user.

50. 5. A towel holder having in combination, a towel roll containing a supply of toweling and adapted for actuation by a force exerted upon the toweling by the user a portion of said towel being freely dispensed, means operable after the portion aforesaid of the toweling has been withdrawn to compel operation of said dispensing mechanism at a comparatively slow rate of speed irrespective of the force exerted upon the toweling by the user, and means including a take up roll operable through said last mentioned means for taking up the soiled toweling.

55. 6. A towel holder having in combination,

means for dispensing toweling adapted to be actuated by a force exerted upon the toweling by the user a portion of said toweling being freely dispensed, and means including 70 a governor operable after the portion aforesaid of the toweling has been withdrawn to retard actuation of said dispensing means irrespective of the force exerted upon the toweling by the user.

7. A towel holder having in combination, 75 a towel roll for dispensing a supply of toweling, a unit mounted for rotation relative to said towel roll and carrying a stud, means for compelling operation of said unit at a comparatively slow rate of speed, a feed roll, a lug upon said feed roll operable after a portion of toweling has been withdrawn from said towel roll to engage said unit stud for limiting further movement of the roll to the speed of said unit.

8. A towel holder having in combination, 80 a towel roll for dispensing a supply of toweling, a unit mounted for rotation relative to said roll and carrying a stud, means for compelling operation of said unit at a comparatively slow rate of speed a feed roll, a lug upon said feed roll operable after movement of the roll to dispense a portion of toweling to engage said stud whereby further movement of said towel roll is restricted to the speed of the unit, and take-up mechanism for the toweling actuated by said unit, said lug also operable to arrest movement of said take up mechanism whereby the amount of soiled toweling taken up by said mechanism substantially equals the toweling withdrawn from said towel roll.

9. A towel holder having in combination, 95 a towel roll for dispensing toweling, a second roll for taking up the soiled toweling, and a friction means actuated through movement of the towel roll by pull of the user for operating the second roll at a slow rate of speed irrespective of the speed at which said towel roll is actuated.

10. A towel cabinet having in combination, 100 means for dispensing toweling, a portion of said toweling being freely dispensed, and means including a governor associated with the means aforesaid for retarding operation of said first mentioned means after the portion aforesaid of toweling has been withdrawn.

11. A towel holder having in combination, 115 a towel roll for dispensing a supply of toweling, means including a spring actuated unit operable automatically after substantially all of the available toweling has been used to take up the final length of toweling, and means 120 requiring the spring to be re-wound to its exact initial tension before a new roll of toweling can be operatively installed in the holder.

12. A towel holder having in combination, 130

a towel roll containing a supply of toweling, a unit mounted for rotation relative to said towel roll and carrying a stud, means for compelling operation of said unit at a comparatively slow rate of speed including a spring, a feed roll, a lug upon said feed roll operable after movement of the feed roll to dispense a portion of the toweling to engage said stud whereby further movement of the feed roll is restricted to the speed of said unit, a second roll operable by said unit for taking up the soiled toweling, and means operable automatically after substantially all of the available toweling has been used to move said lug out of the path of said stud and thereby permit free actuation of said unit for operating said second roll to take up the final length of toweling.

13. A towel holder having in combination, a towel roll containing a supply of toweling, a unit including a spring mounted for rotation relative to said roll and carrying a stud, means compelling the operation of said unit at a comparatively slow rate of speed a feed roll, a lug upon said feed roll operable after movement of the roll to dispense a portion of toweling to engage said stud, thereby restricting further movement of the feed roll to the speed of the unit, a second roll operated by said unit for taking up the soiled toweling, means operable automatically after substantially all of the toweling has been used to separate said stud and lug and thereby permit free actuation of said unit for operating said second roll to take up the final length of toweling, and means requiring the spring for the unit to be re-wound to its exact initial tension before a new supply of toweling can be operatively installed upon the holder.

14. A towel holder having in combination, a towel roll containing a supply of toweling, a spring actuated unit mounted for rotation relative to said roll and carrying a stud, means for compelling operation of said unit at a comparatively slow rate of speed, a feed roll, a lug upon said feed roll operable after movement of the towel roll to dispense a portion of toweling to engage said stud, thereby restricting further movement of the feed roll to the speed of the unit, mechanism operable by said unit for taking up the soiled toweling, means operable automatically after substantially all of the toweling has been used to move said second mentioned lug out of the path of said stud and thereby permit free actuation of said unit to operate said mechanism for taking up the final length of toweling, and means operable upon the installation of a new supply of toweling to prevent said second mentioned lug from moving into operative position until the spring for actuating said unit has been re-wound to its exact initial operating tension.

15. A towel holder having in combination, means for dispensing clean toweling, a por-

tion of said toweling being freely dispensed, and means automatically operable after the portion aforesaid of toweling has been dispensed to retard but allow further actuation of said dispensing means by continued pull of the user.

16. A towel holder having in combination, means for dispensing toweling, a portion of said toweling being freely dispensed, means automatically operable after the portion aforesaid of toweling has been withdrawn to retard but permit further delivery of the toweling and means automatically operable at a comparatively slow constant speed for taking up the toweling withdrawn whereby a convenient length of toweling is always available.

17. A towel holder having in combination, means for dispensing toweling, a take-up means for the soiled towel, a power unit including a spring and means whereby said spring will be tensioned when a towel supply is placed in the holder, said unit having a driving connection with said take-up means and also operatively connected with said towel dispensing means, and means made operative when the towel supply is nearly exhausted for releasing said power unit from its connection with said dispensing means and operate said take-up to wind the final length of towel thereon.

18. A towel holder having in combination, means for dispensing toweling adapted to be actuated by pull of the user on the towel, means becoming automatically operative at a predetermined point in the delivery of the towel to yieldingly resist further delivery thereof, a take-up means having a driving connection with said yielding means, and means for temporarily disconnecting said yielding means from said dispensing means to allow the former to operate said take-up means and withdraw the final length of towel.

19. A towel dispensing apparatus having in combination, means for dispensing toweling, a portion of said toweling being freely dispensed, means for limiting the amount of toweling so withdrawn and means operable upon actuation of the means aforesaid to permit further actuation of said dispensing means at a predetermined speed, said first-mentioned means being also operable to limit the movement of said second-mentioned means.

20. A towel dispensing apparatus having in combination, means for freely dispensing a predetermined length of toweling and means for limiting the length of toweling so dispensed, means operable upon actuation of the means aforesaid to permit further actuation of said dispensing means at a retarded speed, said first-mentioned means being also operable to limit the movement of said second-mentioned means, and means whereby said

first-mentioned means may be made inoperative to limit the movement of said retarding means.

21. A towel dispensing apparatus having in combination, means for dispensing freely a limited length of toweling, and means for regulating the length of toweling so dispensed, including a lug associated with said means, means automatically operable upon actuation of said lug to permit further movement of said dispensing means at a retarded speed, said lug being also operable to limit movement of said retarding means, and means operable when a predetermined length of toweling has been dispensed, whereby said lug is rendered ineffective for limiting the movement of said retarding means.

22. A towel holder having in combination, means for dispensing toweling, a portion of said toweling being freely dispensed and means normally inactive but becoming automatically operable at a predetermined period in the dispensing operation for taking up the toweling after the same has been withdrawn and means whereby said take-up means is compelled to operate at a comparatively slow speed.

23. A towel holder having in combination, a support for a supply of toweling to be dispensed, a feed roll, a power unit including a spring and connected with said feed roll for rotation therewith, a portion of the toweling being freely dispensed by pull of the user thereon, means whereby said feed roll and power unit are compelled to operate at a comparatively slow rate of speed, a second roll operated by said unit for taking up the soiled toweling, and means whereby when substantially all the toweling has been used, the free actuation of said unit by said spring to operate said second roll and take up the final length of toweling is permitted.

24. A towel holder having in combination, a support for a supply of toweling to be dispensed, a feed roll, a power unit including a spring and connected with said feed roll for rotation therewith, a portion of the toweling being freely dispensed by pull of the user thereon, means whereby said feed roll and power unit are compelled to operate at a comparatively slow rate of speed, a second roll operated by said unit for taking up the soiled toweling, means whereby when substantially all the toweling has been used, the free actuation of said unit by said spring to operate said second roll and take up the final length of toweling is permitted, and means whereby said spring must be rewound to its exact initial tension before a fresh supply of toweling can be installed in said holder.

25. A towel holder having in combination, means for dispensing a supply of toweling, a spring operated power unit connected with said dispensing means to be actuated by pull of the user on the towel, said spring being

put under tension by rotation of the towel dispensing means, a take-up roll operatively connected with said power unit for winding up the soiled towel commensurate with the dispensing of the clean towel, and a mechanism associated with said dispensing means and said unit whereby said take-up roll is automatically actuated at a predetermined point to wind up the final length of towel.

26. A towel holder having in combination, a dispensing roll and a soiled towel take-up roll, a spring-operated power unit connected with said dispensing roll to be actuated by pull of the user on the towel, a friction device for yieldingly resisting movement of said dispensing roll when a predetermined length of towel has been freely dispensed, said power unit operating to wind up a certain length of soiled towel automatically when pull of the user on the clean towel ceases.

27. A towel holder having in combination, a roll for dispensing a supply of clean towel, a take-up roll for the soiled toweling, a spring-operated power unit connected with said dispensing roll, said dispensing roll having freedom of initial movement to dispense a predetermined length of towel by pull of the user thereon, means connecting said power unit with said take-up roll for winding thereon a length of toweling equivalent to the length drawn out by the user when pull on the web ceases, said take-up roll connection including means whereby when a predetermined length of soiled towel has been wound an equal length of clean towel may be withdrawn by the user.

In testimony whereof I affix my signature.

TRACY BROOKS TYLER.
